UNITED STATES PATENT OFFICE

2,112,034

ELECTRICAL DISCHARGE DEVICE

Orrin W. Livingston, Schenectady, N. Y., assignor to General Electric Company, a corporation of New York

Application October 22, 1936, Serial No. 106,995

9 Claims. (Cl. 250—27)

The present invention relates to electrical discharge devices, and more particularly to discharge devices which include an ionizable gas or vapor as an operating medium. Devices within this latter classification are normally characterized by the fact that while a discharge may be initiated by the action of the control electrode alone, it may be interrupted only by reducing the anode potential below a critical value.

10 In connection with many uses of "discontinuously controlled" discharge devices of the type specified, it has been observed that their control characteristics tend to be objectionably affected by the sporadic variations in anode to cathode 15 potential encountered in actual practice. In certain cases extreme changes in anode potential occasioned by circuit transients may cause a discharge to be initiated independently of the control electrode potential while, in other cases, potential variations which are insufficient to overcome the effect of the control electrode may so modify the critical control voltage at which a discharge can take place as to render the operation of the device unreliable.

20 In Patents No. 2,044,618 and 2,044,619, assigned to the General Electric Company, I have disclosed and claimed means for shielding the control electrode in such a manner that the first of the above-described effects may be substantially overcome. 25 The present invention is more specifically concerned with the second effect and has for an object the prevention of variations of the critical discharge-initiating voltage of the control electrode with changing anode potential.

30 It is a further object of the invention to shield the control electrode from the main discharge electrodes in such a way that the initiation of a discharge will depend only upon the charging of the control electrode to a constant predetermined voltage.

35 It is a still further object to provide in the vicinity of the control electrode an electrostatic field adapted to favor the initiation of a discharge upon the attainment of a given critical control 40 electrode potential, irrespective of variations in the potential of the anode.

The features of novelty which I desire to protect herein are pointed out with particularity in the appended claims. The invention itself, however, 45 together with further objects and advantages thereof, may best be understood by reference to the following specification taken in connection with the drawing in which Fig. 1 represents in section a discharge device and associated circuit 50 suitably embodying the invention, Fig. 2 illus-

trates similarly a modified construction of the discharge device and an alternative arrangement of the associated circuit, and Fig. 3 is a graph illustrating certain characteristics of the device shown in Figs. 1 and 2.

5 Referring particularly to Fig. 1, I have shown a sealed envelope 1 suitably of glass terminating at its lower end in a reentrant stem 2 and a press 3. Within the envelope there are provided main discharge electrodes including an anode 6 and a cathode 7, of which the latter may suitably comprise an outer cylindrical member enclosing extended electron emissive surfaces heated indirectly by a means which is indicated diagrammatically as a filamentary resistance wire 8 disposed axially within the cylinder. An example of such a cathode is described and claimed in A. W. Hull Patent 1,924,819. The anode is provided with a suitable lead-in connection 11 and similar connections 13, 14, and 15 are sealed through the press 3 and connected to the various elements of the cathode. Between the anode and cathode and surrounding the discharge path which is defined between them there is arranged an electrostatic control member or electrode 17 comprising in the particular case illustrated an annular graphite member supported on a lead-in connection 18. In order to provide a suitable operating medium for these various electrodes the envelope as a whole may contain a substantial quantity of 15 a gas, for example, argon, or a small quantity of a readily vaporizable ionizing medium, for example, mercury. If this last-named substance is employed, it may be introduced as a small globule (indicated at the base of the envelope by 20 the numeral 20).

25 In order to shield the control electrode 17 from the electrostatic field of the anode 6 and thereby to prevent variations in the control characteristic of the tube, my invention provides electrically 30 independent shielding means respectively interposed between the control electrode and the anode and between the control electrode and the cathode. In the particular case illustrated these means comprise a pair of longitudinally extending metal tubular members 23 and 24 which define a shielding chamber substantially enclosing the control electrode. Taken conjointly, these tubular members laterally enclose not only the control electrode but also the entire discharge path 35 up to and including both the anode and cathode so that the complete absence of stray fields proceeding from either of the main discharge electrodes is assured.

The tubular members 23 and 24 are respectively 40

provided with transverse metal baffles 26 and 27, which have small central apertures and which may be secured in place in any suitable and well-known manner. To maintain each of the composite shielding means in proper position with respect to the remaining electrodes conductive supports 28 and 29, 30 and 31 are provided, which supports in turn are mounted on the stem tube 2 by means of clips or rings 33 and 34. One member of each pair of supports is connected to a suitable lead-in connection whereby desired potentials may be impressed on the shielding members 23 and 24.

One mode of utilizing the discharge device described in the foregoing is indicated by the circuit connections diagrammatically shown in Fig. 1. According to the arrangement illustrated, the cathode is supplied with exciting current by means of a heating transformer having a primary 35 and a secondary 36. A suitable value of alternating potential derived from the secondary of another transformer 37 is impressed between the cathode and the anode 6 in series with a translating device such, for example, as a solenoid-controlled circuit breaker or relay. The impedance characteristics of such a device are indicated schematically by a resistance 38 and the parallel combination of a resistance 39 and an inductance 40. As a result of the inductive component of the impedance, transient voltage variations are apt to appear between the anode 6 and the cathode 7 from cycle to cycle after a discharge is once initiated. For this reason the potential required to be impressed on the control electrode 17 to maintain the device recurrently conductive after a discharge has been started may be considerably different from that required to initiate the discharge.

The significance of this fact may best be understood with reference to a particular control circuit such, for example, as that shown in the drawing. In this circuit there is included a photo-sensitive member 48 arranged as one of the arms of a bridge arrangement which also comprises a voltage source 49 and balancing resistances 50 and 51. When the photo-sensitive element is subjected to a light impulse of given intensity its resistance will change, the bridge being thrown out of balance, and a discharge initiating potential impressed on the control electrode 17 through the grid current limiting resistor 52. The setting of the bridge may be such that a definitely predetermined light intensity will be required to cause the initiation of a discharge. However, if the load connected in circuit with the discharge device comprises a relay having the impedance characteristics previously indicated, a decrease in light intensity considerably below the discharge-initiating value may be required before the relay will be again deenergized.

In accordance with my present invention this lag effect, which is obviously objectionable, may be avoided by arranging electrostatic members such as members 23 and 24 on opposite sides of the control electrode and biasing these members positively with respect to the cathode as indicated in Fig. 1. According to the arrangement there shown the member 24 and its associated baffle portion 27 are maintained at a slight positive potential with respect to the cathode 7 by means of a source of direct current biasing voltage 54, while the member 23 is maintained at a still higher positive potential by means of an additional voltage source 53 which is in series 75 with the source 54. In this way the control elec-

trode 17 is electrostatically shielded from the effects of the field in the region of the anode 6, and at the same time a constant accelerating field independent of anode potential is maintained in the chamber surrounding the aforesaid electrode. Thus, electrons drawn from the cathode 7 by the effect of the positive charge maintained on the member 24 may pass through the apertured baffle 27 into the control electrode chamber where they will be subjected to a definite accelerating potential whose value depends upon the relative voltages of the members 23 and 24. While this accelerating potential will not ordinarily be sufficient to produce ionization of the operating medium, its presence will insure the result that when a predetermined critical voltage is applied to the control element 17 enough additional velocity will be imparted to the slowly "drifting" electrons to cause ionization to occur and a main discharge to be initiated. This critical voltage will be independent of the potential existing on the anode 6 (provided of course that that potential is positive and above the ionization potential of the particular operating medium employed) and will be constant for all normal conditions of operation of the discharge device.

An alternative modification of the invention is shown in Fig. 2 in which elements corresponding to those shown in Fig. 1 are similarly numbered. In this embodiment the side walls of the enclosing envelope comprise a pair of tubular metal members 55 and 56 which are insulatingly spaced by a ring of glass 57 sealed to their adjacent extremities. In this case a control electrode 59 is supported between the anode 6 and the cathode 7 by means of lead-in connection 61 sealed through the wall of the glass ring. The ends of the envelope are hermetically closed by means of flanged headers 62 and 63 respectively joined to the extremities of the tubular members 55 and 56. Each of these headers is provided with means for making lead-in connections to the main discharge electrodes, and the lower header bears a depending tubulation 66 which serves during the manufacturing process to exhaust and finally seal the envelope. It will be seen that the tubular members 55 and 56 also constitute a portion of the walls of a chamber which is so formed as to surround the control electrode 59 and which corresponds to the similar chamber described in connection with Fig. 1. As in the previously described arrangement, baffles 64 and 65 are provided interposed respectively between the control electrode and the anode and between the control electrode and the cathode.

The energizing circuit shown diagrammatically in connection with Fig. 2 is adapted to avoid the necessity of a supply of direct current biasing potential. To this end a portion of the potential of a transformer 70 is impressed across a potentiometer resistance 71 which is connected in series with an additional current limiting resistance 72. Portions of the voltage developed across the resistor 71 are impressed on the tubular members 55 and 56 by means of connections 74 and 75. The order of connection is such that these members are positively charged with respect to the cathode whenever the anode is similarly charged. If desired the values of the various sections of the resistor 71 may be so adjusted that only a slight accelerating voltage is developed across the shielding members or alternatively this voltage may be given a higher value such that the potential of the member 55 and its associated baffle 75

65 exceeds the ionization voltage of the operating medium in the envelope. If the latter condition is chosen, the device may be maintained non-conductive by the use of a negative bias impressed 5 on the control electrode 59, and a control or triggering apparatus 76, corresponding for example to the control circuit shown in Fig. 1, may be utilized which is of such nature as to release this negative bias upon proper stimulation thereby 10 to permit a discharge to take place. Under the conditions assumed such a discharge will first occur between the cathode 7 and the positive shielding member 55 (or the baffle 65) from which it may be caused to transfer to the main anode 6 15 by the use of a sufficiently high resistance 78 interposed in the lead 74.

In order to limit the biasing voltage applied to the shielding members to a predetermined constant value means represented as a glow discharge 20 device 81 may be connected across the resistor 71 for governing the potential impressed thereon. The characteristics of a glow discharge device are such that it will become conductive at a definite predetermined voltage and thereafter will support across its terminals a substantially constant 25 voltage slightly lower in value than the breakdown voltage. Consequently the potential developed across resistance 71 will not be permitted to rise to a value in excess of the drop across the device 30 81 irrespective of the variations in voltage current between the anode 6 and the cathode 7. As an ultimate result of these provisions the field in the vicinity of the control electrode 59 may be maintained substantially constant during the 35 periods in which the discharge device as a whole is capable of being rendered conductive, and the initiation of a discharge will depend in all cases upon the application to such control electrode of a perfectly definite and predetermined starting 40 voltage.

The advantageous results of my invention may best be understood by reference to Fig. 3 in which I have shown curves A and B representing respectively variations of critical grid voltage with 45 anode voltage for an unshielded control member and for a control member shielded in the manner described in the foregoing. It will be seen that whereas in curve A a considerable change in the control potential required to initiate a discharge 50 occurs for a given variation in anode potential, in curve B a control characteristic is obtained which is substantially independent of anode potential.

While I have shown particular embodiments 55 of my invention, it will be understood by those skilled in the art that many modifications may be made without departing from the invention, and I aim by the appended claims to cover all such modifications as fall within the true spirit 60 and scope of the invention.

What I claim as new and desire to secure by Letters Patent of the United States is:

1. In an electrical discharge device, an envelope 65 containing a substantial quantity of an ionizable medium, an anode and a cathode arranged within said envelope and defining a discharge path, an electrostatic control member associated with said discharge path and a chamber substantially enclosing said control member, said chamber 70 comprising a pair of electrically independent conducting members each laterally surrounding said discharge path and a pair of transverse conducting baffles each secured to one of said conducting members and adapted during the oper-

ation of said device to shield the control element from the effects of variations in potential of said anode.

2. In an electrical discharge device including 5 relatively spaced anode and cathode members defining a discharge path therebetween, an electrostatic control member between said anode and cathode and electrostatic shielding means associated with said control member, said means comprising a pair of electrically independent metal 10 tubular members conjointly laterally enclosing said anode and cathode and said discharge path, and a pair of transverse apertured metal baffles each secured to one of said tubular members and respectively interposed between said control 15 member and said anode and cathode.

3. An electrical discharge device comprising a sealed envelope, an anode and a cathode arranged within said envelope, an electrostatic control member between said anode and cathode and a 20 chamber substantially enclosing said control member, said chamber comprising a pair of electrically independent conducting members which also constitute portions of the wall of said envelope and a pair of transverse electrostatic 25 shielding members each connected to one of said conducting members and respectively interposed between the control member and said anode and the control and said cathode.

4. An electrical discharge device comprising an 30 elongated envelope enclosing spaced anode and cathode electrodes, a pair of tubular metal members forming portions of the wall of said envelope, means electrically insulating said tubular members from one another, an electrostatic control 35 electrode interposed between the anode and cathode, and a chamber substantially enclosing said control electrode, said chamber being formed partly by portions of said tubular members and partly by a pair of apertured transverse metal 40 baffles each electrically connected to one of the tubular members and interposed between the control electrode and said anode and cathode respectively.

5. In an electrical discharge device, an envelope 45 containing a substantial quantity of an ionizable medium, an anode and a cathode arranged within said envelope and adapted to support a discharge therebetween, a control electrode between said anode and cathode and adapted to control 50 the initiation of a discharge during certain periods of the operation of said device, and means effective at least during said certain periods to maintain in the vicinity of said control electrode a substantially constant accelerating field the 55 magnitude of which is independent of variations in the potential of said anode.

6. In an electrical discharge device, an envelope containing a substantial quantity of an ionizable medium, an anode and a cathode arranged within 60 said envelope to support a discharge therebetween, a control electrode between said anode and cathode and adapted to control the initiation of a discharge during certain periods of the operation of said device, and means including electro- 65 static members arranged on opposite sides of said control electrode effective at least during said certain periods to maintain in the vicinity of the control electrode a substantially constant accelerating field the magnitude of which is independent 70 of variations in the potential of said anode.

7. In combination, an electrical discharge device comprising an envelope containing a substantial quantity of an ionizable medium, an anode and a cathode arranged within said en- 75

- 5 envelope and adapted to support a discharge there-
between, a control electrode between said anode
and cathode and adapted to control the initiation
of a discharge during certain periods of the oper-
ation of said device, a shielding member inter-
posed between the control electrode and said
cathode, a second shielding member electrically
independent of the first and interposed between
the control electrode and said anode, and means
10 effective at least during said certain periods to
maintain said shielding members at predeter-
mined positive potentials with respect to the
cathode, the potential of said second member be-
ing higher than that of the first.
- 15 8. In combination, an electrical discharge de-
vice comprising an envelope containing a sub-
stantial quantity of an ionizable medium, an
anode and a cathode arranged within said en-
velope and adapted to support a discharge there-
20 between, a control electrode between said anode
and cathode and adapted to control the initiation
of a discharge therebetween, a shielding member
interposed between the control electrode and said
cathode, a second shielding member electrically
25 independent of the first and interposed between
the control electrode and said anode, means in-
cluding a source of alternating potential for pro-
ducing intermittent discharges between said
anode and cathode during the recurrent inter-
30 vals when the anode is positive with respect to the
cathode, means for impressing a discharge-in-
itiating potential on said control electrode in de-
- sired relation to the variations of said alternating
potential, and means including a source of biasing
potential for maintaining said shielding mem-
bers at predetermined positive potentials with re-
spect to said cathode during said recurrent inter-
vals, the potential of said second member being 5
higher than that of the first.
9. In combination, an electrical discharge de-
vice comprising an envelope containing an ionizable
medium, an anode, and a cathode arranged
within said envelope and adapted to support a 10
discharge therebetween, a control electrode be-
tween said anode and cathode and adapted to
control the initiation of a discharge, a shielding
member interposed between the control electrode
and said cathode, a second shielding member 15
electrically independent of the first and inter-
posed between the control electrode and said
anode, means including a source of alternating
potential for producing intermittent discharges
between said anode and cathode during the re-
current intervals when the anode is positive with 20
respect to the cathode, means for impressing a
discharge-controlling potential on said control
electrode in desired relation to the variations of
said alternating potential, means including said
source of alternating current for impressing 25
biasing potentials on said shielding members
during said recurrent intervals, and means for
limiting said biasing potentials to a desired value. 30

ORRIN W. LIVINGSTON.
